UNITED STATES PATENT OFFICE.

CLARENCE W. MARSH, OF GREENWICH, CONNECTICUT, ASSIGNOR, BY MESNE ASSIGNMENTS, TO HOOKER ELECTROCHEMICAL COMPANY, OF NEW YORK, N. Y., A CORPORATION OF NEW YORK.

ELECTROLYTIC CELL.

1,075,364.

Specification of Letters Patent.

Patented Oct. 14, 1913.

Application filed January 15, 1912. Serial No. 671,190.

To all whom it may concern:

Be it known that I, CLARENCE W. MARSH, a citizen of the United States, residing at Greenwich, in the county of Fairfield and 5 State of Connecticut, have invented certain new and useful Improvements in Electrolytic Cells, of which the following is a specification.

This invention relates to electrolytic cells 10 of the diaphragm type, and especially to such as are adapted for the electrolysis of alkali-metal chlorids.

The object of the invention is to provide a construction of the above type which is 15 capable of efficient operation at low voltages, and which possesses a high ampere capacity in proportion to the space required for its installation.

For a full understanding of the invention, 20 reference is made to the accompanying drawings, wherein:

Figure 1 is a plan view of one form of cell embodying the invention, one-half thereof being shown in section on the 25 broken line I—I of Fig. 2; Fig. 2 is an elevation of the same, one-half thereof in section on the line II—II of Fig. 1; and Fig. 3 is a vertical section of a portion of the cell on the line III—III of Fig. 1.

30 In said drawings, 1 represents a substantially cylindrical vessel of earthenware or a cement composition resistant to chlorin, and 2 is a cover therefor in the form of an inverted annular trough dipping below the 35 normal liquid-level, luted to the cell body 1, as indicated at 3, and provided with an upwardly-extending connection 4 for the delivery of chlorin.

5 is an annular disk, which may be of like 40 material to the cell body 1, and either integral therewith or set in a suitable cement 6.

The cathode 7 is preferably of steel, perforated throughout its active area, and is applied at its upper margin 8 to the inner face 45 of the depending flange of the cover 2, being reinforced at its margin by a metal ring 9 to which the cathode connector 10 is attached. The cathode plate is formed with a series of substantially radial, inwardly-extending, vertically-disposed recesses 11, which are in open communication with the outer or anode compartment 12, constituting 50 radial extensions thereof. Between the recesses 12 are correlated pockets or recesses 13 constituting radial extensions of the in-

ner or cathode compartment 14. The diaphragm 15, usually of asbestos paper or cloth or a combination of these, overlies the perforated area of the flexed cathode plate on the side thereof adjacent the anodes, and 60 may be cemented or clamped to the cathode or to the adjacent portions of the cell near its upper and lower margins. The upper and lower walls of the outwardly-extending pockets or recesses 13 of the cathode plate 65 are protected and rendered impervious and inactive in any suitable manner, preferably as indicated in Fig. 3, by covering these portions of the plate with an insulating and inert plastic composition 16, interlocking with 70 the plate through its perforations. For this purpose, I may use cement, an insoluble condensation product of phenols and formaldehyde, or a composition thereof, or the like.

The anodes 17, usually of Acheson-graphite, comprise bars or rods disposed in the radial extensions 11 of the anode compartment, and extending upwardly through the cover 2, being luted therein as indicated at 18. The anodes may also be supported from 80 below, as by blocks 27. The several anodes are interconnected through a copper or aluminum ring 19 constituting the positive conductor, and electrically connected with the caps 20 of the individual anodes by 85 straps or bars 21.

The electrolyte, usually a solution of sodium or potassium chlorid, is led to the anode compartment of the cell through a supply-pipe 22, with which is preferably associated any suitable device for maintaining a constant level of liquid in said compartment. In the form illustrated, this device comprises an external supply-vessel 23 having a supply-pipe 24 for the brine, and an 90 overflow 25 at the desired level. Means may be provided for adjusting this overflow in order to control the hydrostatic pressure of liquid in the anode compartment, or a series of overflows may be provided at differing 100 levels, as is well understood in the art. The central or cathode compartment may be covered, as indicated at 28, and the hydrogen evolved may be collected through the pipe 29. The caustic solution is permitted to flow 105 from the cell as rapidly as formed through pipe 26.

In operation, the solution undergoing electrolysis percolates through the diaphragm and cathode into the central compartment 14 110

which may be filled with a mineral oil or other liquid immiscible with aqueous solutions, for purposes well understood in the art. In case the cell is operated at relatively low current density, it is desirable that the exposed portions should be well covered with a suitable heat-insulating material, in order that the best working temperatures may be maintained.

10 I claim:

1. An electrolytic cell comprising a central cathode compartment, an anode compartment surrounding said cathode compartment, a pervious cathode and diaphragm between said compartments, said cathode and diaphragm flexed or bent to provide recesses communicating with said anode compartment, and anodes disposed in said recesses.
2. An electrolytic cell comprising a central cathode compartment, an anode compartment surrounding said cathode compartment, a pervious cathode and diaphragm between said compartments, said cathode and diaphragm flexed or bent to provide substantially radial recesses communicating with said anode compartment, and anodes disposed in said recesses.
3. An electrolytic cell comprising a central cathode compartment, an anode compartment surrounding said cathode compartment, a pervious cathode and diaphragm between said compartments, said cathode and diaphragm flexed or bent to provide recesses communicating with said anode compartment, anodes disposed in said recesses, and means for maintaining a constant level of electrolyte in said anode compartment.
4. An electrolytic cell comprising a central cathode compartment, an anode compartment surrounding said cathode compartment, a pervious cathode and diaphragm between said compartments, said cathode and diaphragm flexed or bent to provide recesses extending radially outward and communicating with the cathode compartment, and anodes located in said anode compartment between the walls of said recesses.
5. An electrolytic cell comprising a cen-

tral cathode compartment, an anode compartment surrounding said cathode compartment, a pervious cathode and diaphragm between said compartments, said cathode and diaphragm flexed or bent to provide recesses extending radially outward and communicating with the cathode compartment, the upper and lower walls of said recesses presenting non-conducting surfaces, and anodes located in said anode compartment between the walls of said recesses.

6. An electrolytic cell comprising a central cathode compartment, an anode compartment surrounding said cathode compartment, a pervious cathode and diaphragm between said compartments, said cathode and diaphragm flexed or bent to provide recesses in lateral and end communication with said anode compartment, and anodes disposed in said recesses.

7. A cell for the electrolysis of alkali salt solutions, comprising a central cathode compartment, an anode compartment surrounding said cathode compartment, a pervious cathode and diaphragm between said compartments, said cathode and diaphragm having pockets extending into said anode compartment and provided with imperforate upper and lower walls, and anodes disposed in the recesses between said pockets.

8. A cell for the electrolysis of alkali salt solutions, comprising a central cathode compartment, an anode compartment surrounding said cathode compartment, a pervious cathode and diaphragm between said compartments, said cathode and diaphragm having pockets extending into said anode compartment and provided with inclined, imperforate upper and lower walls, and anodes disposed in the recesses between said pockets.

In testimony whereof I affix my signature in presence of two witnesses.

CLARENCE W. MARSH.
